UNITED STATES PATENT OFFICE.

CHARLES W. SLOCUM, OF NEWARK, NEW JERSEY.

GRIP FOR PENHOLDERS.

1,168,342.

Specification of Letters Patent. Patented Jan. 18, 1916.

Application filed April 30, 1915. Serial No. 24,916.

To all whom it may concern:

Be it known that I, CHARLES W. SLOCUM, a citizen of the United States, and a resident of Newark, county of Essex, and State of New Jersey, have invented certain new and useful Improvements in Grips for Penholders, of which the following is a specification.

This invention relates to an improved grip for pen holders or for pencils, but in this specification it is described as applied to a pen holder, but it will be understood that it can be used on any kind of writing instrument, being designed to receive the thumb and two first fingers of the hand and to provide rests for the thumb and these fingers, when they are in proper position, for writing with freedom and comfort and at the same time to give sufficient power so as to make the writing easy.

The grip is designed particularly for the use of pupils in writing, and is designed to put the hand in a position that overcomes the tendency to write by gripping the fingers around the writing instrument in a cramped position and writing with a finger movement, thus encouraging the arm movement, and while the grip is thus particularly adapted for pupils, it can also be used by writers in general and conduces to greater comfort and more perfect writing.

The grip can be made in any suitable form and the finger rests are suitably disposed around a shank of the writing implement, the preferred form described in the specification and illustrated in the drawing consisting of a sleeve which can be slipped over a pen holder or a pencil and can be made to fit a certain size holder, or it can be made of spring material and split so that it is adapted for a number of different sizes, being held in place by the spring action of the material, and I also desire to make the finger rests of the same size as the sleeve, the preferred way being by striking up the finger rests from the material, thus cheapening the cost of production and making a grip that is of good appearance.

In the drawing I have illustrated the improved grip as applied to a pen holder, and in Figure 1 I show a perspective view of the grip, a pen holder being shown in dotted outline and a human hand being also shown in dotted outline to illustrate the position of the grip in the hand. Fig. 2 is an enlarged front view of the grip. Fig. 3 is a

perspective view with the grip shown in Fig. 1 turned over so as to illustrate the bottom side thereof, and Fig. 4 is a section on line 4, 4, in Fig. 3.

In the drawing I illustrate an ordinary pen holder 10 which is provided with the improved grip, the grip in the illustration being of the type that is formed of spring material, preferably spring metal, bent into the shape of a sleeve, this in order to make it adjustable and to give it the proper spring being usually split longitudinally. The sleeve 11 is preferably made of spring metal and I have found in order to make it light that aluminum is a desirable material to use. The sleeve 11 is split as at 12, which split can be suitably disposed as desired, but I prefer to form the split so that it avoids the finger rests and leaves enough space between the finger rests and the split to prevent weakening of the material and thus insure it against splitting.

On the top of the sleeve which forms the shank or grip of the holder I place a finger rest 13 which can be slightly hollowed or absolutely flat, and when the grip is in the form of a sleeve the finger rest 13 is formed of a tablet struck up from the sleeve, the material forming the tablet being forced away, thus forming the openings 14. The tablet is thus substantially tangential to the sleeve and I may provide the finger rest with suitable means for preventing slipping of the finger from the tablet, this being usually done by providing a marginal flange 15. The tablet 13 on the top of the holder is arranged near the forward end of the grip, the forward end, for identification, being that end which is nearest to the end of the pen holder that receives the pen point 16. At a material distance in rear of the tablet on the top of the grip is a substantially vertically arranged tablet 17 which forms a rest for the thumb and is provided with similar means for preventing the slipping of the thumb, in the form shown this being done by providing the tablet 17 with the marginal flange 18. These tablets when struck up from the shell of the grip, when the grip is made in the form of a sleeve, are tangential and are connected at points with the undisturbed material of the shell, these connecting strips being substantially flush with the outside of the sleeve as at 19 and 20.

The tablets are preferably made of semi-circular halves which are struck up from

both sides of said flush parts 19 and 20 to form the tangential tablets of sufficient stiffness and adequate surface.

On the side of the grip opposite the side 5 on which the vertical tablet 17 is placed and at the lower part thereof is arranged a wing 21 struck up from the material of the sleeve 11 and being obliquely arranged slightly in rear of the tablet 13. The wing provides a 10 rest for the side of the second finger, and when the second finger rests against the wing it is held against slipping back along the grip, as will be readily seen from Fig. 1, and in order to prevent any unpleasant projection 15 in the groove or channel in which the second finger rests I prefer to provide a part 22 which is bent slightly outward substantially parallel with the wing 21, but this latter portion 22 is not absolutely essential, but it does, however, assist the second finger in placing itself in position against the wing 21. These finger rests are so disposed that they indicate proper positions of the thumb and the first two fingers of the 20 hand and tend to overcome any tendency that a pupil might have to cramping the fingers and to writing with a finger movement which instructors find is a difficult fault to correct when once established. To 25 further prevent any tendency to cramp the fingers, and to prevent, especially the index finger, from riding back along the grip, I provide a raised portion in rear of the top tablet of the grip, this raised portion being 30 of any suitable form, the grip as illustrated in the drawing having the projection formed in the shape of knobs or protuberances 23 which, while they are not sharp, are small enough to provide gripping surfaces for the 35 finger and prevent its slipping back along the grip.

The tangential disposition of the tablets gives them an amount of spring which forms a resilient surface against which the thumb 40 and forefinger are pressed, and in this way 45 the fatigue of grasping the pencil or pen is minimized.

Having thus described my invention, I 50 claim:

1. A grip for pen holders comprising a shank having a tablet on the top near the front, a second tablet at one side and ver-

tically arranged thereon in rear of the first mentioned tablet, and an obliquely arranged wing projecting from the lower part of the 55 side opposite the second tablet, the wing being slightly in rear of the first tablet.

2. A grip for pen holders comprising a shank having a substantially flat horizontal tablet on the top near its front end, a substantially flat vertical tablet on one side of the shank in rear of the horizontal tablet, and a wing projecting from the lower part of the side opposite the vertical tablet, the wing being slightly in rear of the horizontal 60 tablet.

3. A grip for pen holders comprising a sleeve having a tablet struck up tangentially therefrom near its front end at the top, a second tablet struck up tangentially therefrom on one side in rear of the first tablet, the second tablet being vertically arranged, and a wing struck up from the sleeve at a point slightly in rear of the first tablet and at the lower part of the side opposite the side 75 on which the second tablet is placed, the wing being obliquely arranged with its forward upper end tangential to the sleeve.

4. A grip for pen holders comprising a sleeve having a tablet struck up therefrom 80 near its front end at the top, a second tablet struck up therefrom on one side in rear of the first tablet, the second tablet being vertically arranged, a wing struck up from the sleeve at a point slightly in rear of the first 85 tablet and at the lower part of the side opposite the side on which the second tablet is placed, and transversely arranged raised portions struck up from the sleeve immediately in rear of the first-mentioned tablet 90

5. A grip for pen holders comprising a split sleeve of sheet material, semi-circular parts struck up therefrom to form a tangential tablet on the top near its front end, semi-circular parts struck up therefrom to 95 form a second tangential tablet vertically arranged on one side in rear of the first tablet, and an obliquely arranged wing at the lower part of the side opposite the second tablet and slightly in rear of the first tablet. 100

In testimony that I claim the foregoing, I hereunto set my hand, this 29th day of April, 1915.

CHARLES W. SLOCUM.
